UNITED STATES PATENT OFFICE.

LOUIS H. DUPONT, OF NASHVILLE, TENNESSEE.

VENDING-MACHINE.

972,350.

Specification of Letters Patent. Patented Oct. 11, 1910.

Application filed December 7, 1909. Serial No. 531,868.

To all whom it may concern:

Be it known that I, LOUIS H. DUPONT, a citizen of the United States, residing at Nashville, in the county of Davidson and State of Tennessee, have invented certain new and useful Improvements in Vending-Machines, of which the following is a specification, reference being had to the accompanying drawings.

10 This invention relates to certain new and useful improvements in coin actuated vending machines and has for its primary object to provide a machine adapted for the vending of newspapers and periodicals.

15 Another object is to provide adjustable actuating mechanism which will permit of the vending of papers or periodicals varying in price, whereby the papers may be discharged by the insertion of a single coin or 20 two or more coins, the actuating elements being inoperative until the proper coin or coins are inserted in the machine.

25 A further object resides in the provision of means automatically operated to close the coin chute after all of the papers have been discharged from the machine.

30 A still further object is to provide automatically operated means whereby the coin or coins will be removed from the positions in which they occupy when the operating mechanism is actuated.

35 With these and other objects in view, the invention consists of the novel construction, combination and arrangement of parts hereinafter fully described and claimed, and illustrated in the accompanying drawings, in which—

40 Figure 1 is a longitudinal section of a machine constructed in accordance with the present invention; Fig. 2 is a horizontal section taken on the line 2—2 of Fig. 1, the operating mechanism being shown in elevation; Fig. 3 is a transverse section taken on the line 3—3 of Fig. 1; Fig. 4 is an enlarged detail section taken on the line 4—4 of Fig. 2; Fig. 5 is a detail section taken on the line 5—5 of Fig. 4; Fig. 6 is a detail view illustrating the coin slot closing means; Fig. 7 is a fragmentary view of the carrier partly 45 in section showing the means for charging the machine; Fig. 8 is a detail perspective view of one of the paper supporting members; and Fig. 9 is a similar view of the adjustable coin engaging pin.

50 Referring to the drawings 5 indicates a

casing in which a frame 6 is disposed. This frame has secured thereon the bearings 7 which receive the ends of the transverse shafts 8. Sprockets 9 are secured adjacent to the ends of each of these shafts, and the 60 endless link chains 10 are movable by these sprockets. Supporting bars 11 are secured to and spaced from the longitudinal side bars of the frame 6 and are adapted to support the upper stretch of the sprocket chains 65 to prevent the same from sagging. The links of these chains are pivoted to each other by means of the transversely extending parallel rods 12 which extend between the two chains and space the same. The 70 teeth of the sprockets 9 engage with these rods and move the endless chains 10 about the spaced shafts 8. U-shaped carrying members 13 have the ends of their vertical portions pivotally disposed upon these rods 75 adjacent to the chains 10 and between the same. This pivotal connection of the members 13 is shown in detail in Figs. 7 and 8 and it will be noted that the ends of the wires are loosely coiled about the pivot rods 80 12 as shown at 14 and the extremities 14' thereof extend in opposite directions and over the next adjacent pivot rod between the upper stretches of the chains. These U-shaped members are arranged in spaced 85 parallel relation and receive between them the papers or periodicals A and as the chains are intermittently moved, the paper will occupy an intermediate position between its normal vertical position and the position of 90 the members 13 when it is discharged. These various positions of the members 13 as they move around the sprockets 9 are clearly shown in Fig. 7, the intermediate position of the paper being indicated at B 95 and the position of the members at which the papers are discharged is indicated at C. When the members 13 are moved to the latter position, the paper will gravitate downwardly and outwardly from the members 100 upon an inclined plate 15 and through a slot or outlet 15' in the forward lower end of the casing 5.

The carrier chains are adapted to be intermittently moved by the rotation of the shafts 105 8 which is produced by the insertion of the proper coin into the coin slot 16. This coin slot extends into a cylindrical housing 17 which is secured to one side of the casing 5 opposite the end of the forward shaft 8. 110

The housing is provided with a hinged cover plate 18 which carries a lock whereby the cover may be securely locked in position to prevent the coins being removed by unauthorized persons. The end of the shaft 3 projects beyond the side of the casing 5 and into the housing and has rigidly secured thereon a ratchet 19. Loosely mounted upon the end of this shaft on each side of the ratchet there is a plate 20 formed as shown in Fig. 4. The lower ends of these plates are enlarged and extend inwardly to receive between them the operating lever 21 which may be conveniently secured to the plates by means of a screw 22. The upper ends of the plates 20 are connected as shown at 23 in a similar manner to their lower ends, through which portion an adjustable pin has threaded engagement. One end of this pin is formed with a reduced extension 25 for a purpose which will hereinafter appear. Also loosely mounted on the shaft 8 are the bell crank levers 26 which extend upwardly and rearwardly therefrom, the rearwardly extending arm of these levers having secured thereto a retractile spring 27, and a similar spring 28 is secured at one end to the plates 20. The other ends of each of these springs is secured to the housing in any desired manner.

A pawl 29 is pivoted between the ends of the vertically extending arms of the bell crank levers and is normally held out of engagement with the teeth of the ratchet 19 by means of the springs 30. The inner end of this pawl is disposed vertically at an angle to the body portion thereof as shown at 31 and an adjustable pin 32 has threaded engagement therein. This pin is positioned opposite to the pin 24, and is adapted to be engaged by the coin in the operation of the mechanism. The coin chute or conveyer 16 terminates at a point above and between these two adjustable pins and is adapted to discharge the coin against the reduced extension 25 of the pin 24, the coin lodging and being supported upon a shoulder 20' formed by the upper reduced ends of the spaced plates 20. This, however, is only the case when a five cent piece is required for the purchase of the paper and the actuation of the carriers.

When it is only necessary to insert a penny for the purchase of the paper, the adjustable screw 24 is turned one-half of a revolution, and the extension 25 positioned upon the lower portion thereof or opposite to the position shown in Fig. 4. The pin 32 is also adjusted inwardly until the proper distance between the ends of the respective pins is secured so that the pawl 29 will be thrown into engagement with the ratchet teeth. This actuation of the parts is caused by pressure being brought to bear upon the lever 21 which moves downwardly in a slot in the casing

against the tension of the spring 28. This movement disposes the coin against the end of the pin 32, and causes the extension 25 of the pin 24 to bear thereon and force the outer end of the pawl 29 into engagement with the teeth of the ratchet 19 which as it is rigidly secured upon the shaft 8 will impart rotative movement thereto and move the endless carrier chains 10. This movement of the chains will move the member 13 carrying the paper and positioned as shown at B, to the position indicated at C from whence the paper will be discharged through the outlet 15 in the casing 5.

In order to prevent a repeated actuation of the machine by means of the same coin, I provide a pivoted arm 33 which is carried upon the upper end of a vertical arm 34 formed integral with one of the plates 20. This discharging member 33 extends above the pivotal point thereof as shown at 33' and is adapted to contact at the end of the movement of the carrier chains with an operating member or block 35 secured to one side of the coin chute 16. The outer edge of this block is beveled or inclined outwardly and forwardly and is adapted to gradually force the lower curved end of the member 33 across the position occupied by the coin. This movement will throw the coin to one side 95 of the elements of the actuating mechanism and deposit it in the bottom of the housing.

In order to prevent the insertion of a coin or coins into the machine after the last paper has been discharged therefrom, I form one of the vertical portions of the end member 13 with an extension 36 which is adapted to contact with an arm 37 pivoted upon the side of the housing 17. This lever 37 carries upon its upper end a laterally extending plate 38 which is normally positioned rearwardly of the coin slot 16. When the lever is engaged by the extension 36, this plate will be moved over the upper end of the coin slot and close the same. The pivotal movement of the lever 37 is limited by a stop 39 which is secured in the side of the housing. In this manner the insertion of coins into the machine after the papers have been entirely discharged therefrom will be prevented.

The end of the shaft 8 upon which the actuating mechanism is mounted is squared to receive a crank by means of which the shaft may be manually rotated to reverse 120 the movement of the carrier chains to return the members 13 to their normal positions. After all of the papers have been discharged, the members 13 will depend from the lower stretch of the chains 10. Upon reversing the movement of the carrier chains the members will be moved upwardly around the end sprocket, the extremities of said members engaging upon the rod 12 immediately in advance thereof. As these 130

members are brought into the position indicated by the letter B, a paper is placed thereon. As each successive receiving member 13 is provided with a paper, they are moved into their normal vertical position, the papers being disposed between the adjacent members. The casing 5 is provided with a hinged plate 40 which closes the forward end thereof. This plate is supported 10 in its open position by means of the chains 41 secured to the opposite edges thereof and to the casing. When in this position the plate may support the papers to be fed upon the members 13 as they are moved rearwardly by the carrier chains. When each 15 of the receiving members has been provided with a paper, the projection 36 will have engaged the pivoted lever 37 and moved the same rearwardly to open the upper end of 20 the coin chute 16 so that the mechanism may be actuated to discharge the papers in the manner previously described.

From the foregoing it will be seen that I have provided a machine for vending 25 newspapers and periodicals which is absolutely positive in its operation, and is of such construction that fraudulent operation is rendered impossible. By providing the adjustable pins 24 and 32, the machine may 30 be adjusted so that when Sunday papers are sold and the price of five cents is charged, the machine cannot be operated by any other coin, but when week-day papers are vended which are sold at one cent or two cents, the 35 adjustment of the pins may be regulated so that the insertion of the proper coin or coins in the machine will be required before a paper can be obtained. It will be obvious 40 that the carrier chains may be made in any desired length and as many of the members 13 provided as may be preferred. While the device is primarily adapted for vending newspapers, it will be understood that it may be also used for the vending of various 45 other articles such as books, candy, etc. The arrangement of the various elements comprising the actuating mechanism are such that the machine is not liable to get out of order and but few repairs will be required. 50 The expense incident to the construction of a machine of this character is also reduced to a minimum as but few parts of simple form are required.

While the construction shown and described sets forth what I believe to be the preferred embodiment of the invention, it will be understood that numerous minor modifications may be resorted to without departing from the spirit or sacrificing any 60 of the advantages of the invention.

Having thus described the invention, what is claimed is:

1. In a delivering mechanism for vending machines, parallel shafts, endless carrier 65 chains traversing said shafts, a plurality of

parallel rods connecting said chains, an article receiving member loosely mounted upon each of said rods, each of said members having engagement with the next adjacent rod whereby said members are supported 70 vertically above the carrier chains, said rods being adapted to support the members at an angle to the forward end of the carrier chains to receive or discharge an article to be vended, and means for moving said carrier. 75

2. In a delivering mechanism for vending machines, parallel shafts, endless carrier chains traversing said shafts, a plurality of parallel rods connecting said chains, an article receiving member loosely mounted upon 80 each of the rods, each of said members having engagement with the next adjacent rod upon each side of the rod upon which said member is mounted, said engaging portions being adapted to support the members between the carrier chains and to hold the same at an angle to said chains to deliver or receive an article to be vended, and means for moving the carrier. 85

3. In a delivering mechanism for vending 90 machines, parallel shafts, endless carrier chains traversing said shafts, parallel rods connecting the chains, an article receiving member loosely mounted upon each of said rods, means engaging with each of the rods 95 adjacent to that on which the members are mounted to support said members above the carrier chains and to successively hold said members at an inclination to the forward end of the carrier to receive or deliver an 100 article to be vended, and means for moving said carrier.

4. In a delivering mechanism for vending machines, parallel shafts, intermittently movable carrier chains traversing said 105 shafts, a plurality of spaced rods connecting said chains, a U shaped article receiving member having its extremities loosely coiled on said rods, said members being normally disposed above the upper stretch of the carrier chains in vertical parallel relation, the extremities of said members being laterally extended and engaged upon the next adjacent rod whereby said members will be successively disposed at an inclination to 110 the forward end of the carrier chains to deliver the article carried thereby, and means for moving said carrier. 115

5. In a delivering mechanism for vending 120 machines, parallel shafts, endless carrier chains traversing said shafts, spaced rods connecting said chains, wire U shaped article receiving members having their extremities coiled about said rods, and extended laterally in opposite directions for engagement 125 with the adjacent connecting rods whereby said members are supported above the chains in vertical parallel relation, and means mounted upon one of the carrier shafts for intermittently moving said chains to suc- 130

cessively dispose the article receiving members at an inclination to the forward end thereof to deliver the article carried thereby.

6. In a delivering mechanism for vending machines, the combination with a casing having a hinged cover adapted to support a number of articles to be vended when opened, the front of said casing having an opening therein and an article receiving plate extending through said opening into the casing, an endless carrier arranged in said casing, a plurality of U shaped article receiving members carried by said carrier and normally disposed in vertical parallel relation above the same, means for intermittently moving said carrier, means carried by each of said article receiving members for successively disposing said members at an angle to the forward end of the carrier to

deliver an article through the opening in the casing at the end of each intermittent movement of the carrier, and means carried by one of said members for rendering the carrier operating means inoperative when the machine has become exhausted, the movement of said carrier being manually reversed to successively position said members to receive one of the articles to be vended, said articles when the machine is completely charged being vertically positioned above the carrier between said members.

In testimony whereof I hereunto affix my signature in the presence of two witnesses.

LOUIS H. DUPONT.
